FREDERICK J. HARDMAN, OF DAYTON, OHIO, ASSIGNOR, BY MESNE ASSIGNMENTS, TO
DELCO-REMY CORPORATION, OF DAYTON, OHIO, A CORPORATION OF DELAWARE

ENGINE STARTING APPARATUS

Application filed July 28, 1924. Serial No. 728,531.

This invention relates to electrical starting apparatus for internal combustion engines and more particularly to the type of apparatus which includes a motor and connections between the motor and engine comprising a pinion adapted to engage and drive a gear connected with the engine to be started. Said connections comprise means whereby the pinion will be automatically demeshed

10 from the engine gear when the engine becomes self-operative. The pinion is moved manually into mesh with the engine gear by a mechanism including a pedal or other devices controlled by the operator. The pedal is 15 automatically disconnected from the pinion after the pinion has been meshed with the engine gear so that automatic demeshment of the pinion in the manner referred to may take place regardless of failure to release 20 the pedal after the engine starts. In this type of apparatus the pedal is used to operate a switch for controlling the motor.

One of the objects of the present invention is to improve this type of apparatus by 25 effecting the substantially complete driving engagement of the pinion and engine gear before the motor is operated so that the teeth of the pinion and gear will be subjected to the minimum shock.

30 Further objects and advantages of the present invention will be apparent from the following description, reference being had to the accompanying drawings wherein a preferred embodiment of one form of the present invention is clearly shown.

35 Figs. 1 and 2 of the drawings are fragmentary side views partly in section showing a form of the present invention, in normal position and in cranking position, respectively. 40 Fig. 3 is a fragmentary plan view partly in longitudinal section of the engine gear, pinion and pinion shifting mechanism shown in the other figures.

45 Referring to the drawings, the engine to be started is represented by a flywheel gear 20 adapted to be engaged by a pinion 21 slidable along a motor shaft 22 and against a stop collar 23 attached to the shaft by pin 24. The shaft 22 is provided with a spirally 50 splined portion 25 and supports the arma-

ture 26 of an electrical motor 27 having a field frame 28. Frame 28 is attached to a gear housing 29 which supports a bearing 30 for the right end of shaft 22. The left end bearing, not shown, is carried by the frame 28. Between the stop collar 23 and a plane bearing surface 31 provided by housing 29 there is located a thrust washer 32.

The splined portion 25 of shaft 22 is threadedly engaged by sleeve 35 provided with flanges 36 and 37 defining a groove 38. Sleeve 35 is provided with diametrically opposed and longitudinally extending slots 39 which receive pins 40 extending through the hub 41 of pinion 21. The hub 41 is provided with a recess 42 for receiving the splined portion of shaft 22 and the sleeve 35. The pinion 21 carries a flange 43 for receiving pressure exerted by a spring 44, of the bed spring type, having its largest turn (indicated by the small cross hatched circle 45) retained as shown within the cylindrical wall of the housing 29 and located against a plurality of lugs 46.

The pins 40 are retained in place by a sleeve 50 adapted to fit snugly around the hub 41 and pinion 21. Sleeve 50 is provided with diametrically opposed slots each including a notch 51 slightly larger in diameter than the largest diameter of the pin 40, and including a notch 52 less in diameter than the largest diameter of pin 40 but slightly greater in diameter than the grooved portion 53 of pin 40. The pins 40 are assembled in the position shown in the drawings after the sleeve 50 has been adjusted along the hub 41 to bring the notches 51 opposite the holes provided in the hub 41 for receiving the pins 40. Then the sleeve 50 is moved into the position shown to lock the pins in place by the movement of the notched portions 52 into the grooves 53 of the pins. The sleeve 50 is retained in locking position by screw 54.

The mechanism for operating the sleeve 35 includes a pedal 60 connected by rod 61 with a lever 62 fitted on rod 63 carried by housing 29. The lever 62 includes an arm 64 carrying a pivot 65 for a latch 66. The latch 66 is provided with a hook 67 adapted to be moved through an opening 68 provided in the yoke 100

69 which connects levers 70, pivoted on rod 63 and each having an end 71 received by the groove 38 of sleeve 35. A spring 75 is attached at one end by screw 76 to the housing 29. The other end of spring 75 passes through a hole 77 provided in latch 66. In order to maintain the lever 62 normally in the position shown in Fig. 1, a spring 80 is located between the pedal 60 and a cup-shaped member 81 surrounding the rod 61 and attached to the floor board 82 of the vehicle propelled by the engine to be started. The spring 80, by acting upon the spring 75 through the pivot 65 and the latch 66, causes the spring 75 to be conditioned for biasing the latch 66 in a counterclockwise direction to cause the latch to be connected with the lever 70.

The motor switch 85 includes casing 86 attached by screw 87 to motor frame 28. Switch 85 includes a plunger 88 carrying within the switch casing a movable contact, not shown, one being connected with the motor circuits and the other with a terminal 89 for making connections with the storage battery.

The invention operates in the following manner. To start the engine the pedal 60 is pressed downwardly to cause the lever 62 to move toward the switch 85. Motion is transmitted from lever 62 to lever 70 through the latch 66 thereby causing the spring 44 to be released to move the pinion 21 into contact with the gear 20 while the sleeve 35 moves spirally toward said gear. Should the teeth of the pinion 21 collide with the teeth of the gear 20 as shown in Fig. 3, motion of the pinion will be temporarily arrested. However, the spiral motion of the sleeve 35 relative to the pinion 21 may continue by reason of the pin and slot connection between these members. During endwise movement of the sleeve 35 along the shaft 22, sleeve 35 will rotate relative to the shaft 22 sufficiently to cause the pinion 21 to rotate into a position for meshing with the gear 20 while being yieldingly pressed against the gear 20 by the spring 44. After this registration has been obtained, continued pressure upon the pedal 60 causes the pinion 21 to move into full engagement with the gear 20 and to move against the stop 23. When the pinion 21 is closely adjacent the stop 23 the switch 85 is closed by the engagement of lever 62 with plunger 88, and thereafter the motor operates to crank the engine.

The operation of the motor tends to urge the pinion 21 against the stop 23 and to relieve the pressure between the engaging surfaces of the lever yoke 69 and the latch hook 67. When this pressure is relieved, the spring 75, then biased to produce clockwise rotation of the latch 66, will be released to effect the disengagement of the latch 66 from lever 70. Therefore, when the engine becomes self-operative, automatic disengage-

ment of the pinion from the engine gear will not be prevented by reason of failure to release the pedal 60.

When the engine becomes self-operative and the gear 20 tends to drive the pinion 21, this driving pressure is transmitted through the pins 40 to the sleeve 35 causing the latter to be threaded along the spirally splined shaft 22. The automatic demeshing of the pinion 21 causes the sleeve 35 to move against a stop 90 surrounding the shaft 22. The sleeve 35 is held in this position by a spring 91 coiled around the rod 63 having an end 92 bearing against the frame 28 and an end 93 bearing against the lever yoke 69.

Release of the pedal 60 permits the sleeve 80 to return the lever 62 to normal position wherein the latch 66 is biased by the spring 75 into meshing connection with lever 70, as shown in Fig. 1. The switch plunger 88 is returned to switch open position by spring 95 located between the plunger and the switch case 86.

During movement of the pinion 21 into contact with the gear 20 the spring 44 continues to bear against the flange 43 so that the relative endwise location of the sleeve 35 and pinion 21 will be maintained as shown in Fig. 1. Therefore if abutting of the pinion teeth against the gear teeth should occur before meshing the pinion 21 with the gear 20 there will be provided sufficient relative endwise movement between the sleeve 35 and pinon 21 to enable the sleeve to be threaded along the shaft to rotate the pinion into a registering position. Meshing of the pinion with the gear is facilitated also by bevelling the ends of the pinion teeth as indicated at 21a. After the pinion 21 has been meshed with the gear 20 the sleeve 35 will move within the recess 42 of the pinion hub 41 until the left end of the slots 39 bear against the pins 40. If the engine should fail to start after the gears have been meshed the motor switch may be opened by release of the pedal 60. Motion of the pedal 62 sufficient to permit the switch to open will occur since the sleeve 35 may be moved away from the pinion 21 until the pins 40 are engaged by the right-hand ends of the slots 39.

During the return movement of the pinion 21 to normal position the flange 43 is engaged again by the spring 44 so that the relative location of sleeve 35 and pinion 21 will be restored to normal as shown in Fig. 1.

One of the advantages of the present invention is that the pinion 21 may be moved manually into substantially full engagement with the engine gear 20 before the motor switch is closed. By using such apparatus, there is the least liability of damage especially to the gear teeth.

While the form of embodiment of the invention as herein disclosed, constitutes a preferred form, it is to be understood that other

forms might be adopted, all coming within the scope of the claims which follow.

What I claim is as follows:

1. Engine starting apparatus comprising, in combination, a motor; a spirally splined shaft driven thereby; a sleeve threadedly engaging the shaft; a pinion slidable along the shaft into mesh with a gear connected with the engine to be started; a driving connection between the pinion and sleeve permitting endwise movement of the sleeve relative to the pinion whereby, if endwise movement of the pinion is prevented by abutting of the pinion teeth and gear teeth, spiral motion of the sleeve along the shaft may be continued in order to rotate the pinion into registration with the gear; a motor switch, and means for moving the sleeve and pinion and for closing the switch when the pinion is in substantially full engagement with the gear.

2. Engine starting apparatus comprising, in combination, a motor; a spirally splined shaft driven thereby; a sleeve threadedly engaging the shaft; a pinion slidable along the shaft into mesh with a gear connected with the engine to be started; a pin and slot driving connection between the pinion and sleeve permitting endwise movement of the sleeve relative to the pinion whereby, if endwise movement of the pinion is prevented by abutting of the pinion teeth and gear teeth, spiral motion of the sleeve along the shaft may be continued in order to rotate the pinion into registration with the gear; a motor switch; and means for moving the sleeve and pinion and for closing the switch when the pinion is in substantially full engagement with the gear.

3. Engine starting apparatus comprising, in combination, a motor; driving connections for connecting the motor and engine including a motor driven spirally splined shaft and a pinion normally drivingly connected with said splines and adapted to mesh with a gear connected with the engine to be started; a device for moving the pinion axially into mesh with the engine gear and for causing the pinion to be rotated while being urged against the engine gear in order to bring the pinion into meshing registration with the engine gear in case of gear tooth abutment; a manually operable member for actuating said device; and a controller for the motor arranged to be operated by the manually operable member only after the pinion is at least partly meshed with the engine gear.

4. Engine starting apparatus comprising, in combination, a motor; a spirally splined shaft driven by the motor; an endwise movable and rotatable member engaging said splines; a pinion adapted to move endwise into mesh with a gear of an engine to be started; driving connections between the pinion and member providing limited endwise movement of the pinion relative to said

member; a spring normally urging the pinion endwise toward the engine gear; a motor switch; and means for moving the member and pinion and for closing the switch.

5. Engine starting apparatus comprising, in combination, a motor; a spirally splined shaft driven by the motor; an endwise movable and rotatable member engaging said splines; a pinion adapted to move endwise into mesh with a gear of an engine to be started; pin and slot driving connections between the pinion and member providing limited endwise movement of the pinion relative to said member; a spring located between the pinion and a stationary part for urging the pinion toward the engine gear; a motor switch; and means for moving the member and pinion and for closing the switch.

6. Engine starting apparatus comprising, in combination, a motor; means for connecting the motor with the engine including a pinion movable into mesh with a gear of the engine and including provisions whereby when the pinion is partly meshed with the engine gear operation of the motor will cause the pinion to be completely meshed, and whereby the pinion will be automatically demeshed when the engine becomes self-operative; a manually operable member; a device actuated by the manually operable member for moving the pinion into mesh with the engine gear and for causing the pinion to be rotated while being urged against the engine gear in order to bring the pinion into meshing registration with the engine gear in case of gear tooth abutment; a motor controller having its actuating member operated by the manually operable member, and spaced normally at such a distance from the manually operable member that the motor controller is not operated to start the motor until after the pinion is substantially meshed with the gear; and means for automatically disconnecting the manually operable member from said device after engine starting begins and before the engine becomes self-operative.

7. Engine starting apparatus comprising, in combination, a motor; a spirally splined shaft operated by the motor; a pinion drivingly connected with the shaft through said splines and adapted to move axially into mesh with a gear of the engine to be started; a manually operable member; a device actuated by the manually operable member for moving the pinion axially into mesh with the engine gear and for causing the pinion to be rotated while being urged against the engine gear in order to bring the pinion into meshing registration with the engine gear in case of gear tooth abutment; a motor controller having its actuating member operated by the manually operable member, and spaced normally at such a distance from the manually operable member that the motor con-

troller is not operated to start the motor until after the pinion is substantially meshed with the gear; and means for automatically disconnecting the manually operable member 5 from said device after engine starting begins and before the engine becomes self-operative.

8. Engine starting apparatus comprising, in combination, a motor; a shaft operated thereby; means for connecting the shaft with 10 the gear of an engine to be started and including a pinion connected with the shaft for rotation therewith and slidable along the shaft into mesh with the gear, and including provisions whereby the pinion will be automatically 15 demeshered from the gear when the engine starts; a device for moving the pinion and for rotating it prior to meshing in case of abutment with the engine gear, while the pinion is being pressed against the engine 20 gear; a manually operable member for operating said device; and means for automatically disconnecting the manually operable member from said device after the pinion 25 has been meshed with the gear and before the engine starts.

9. Engine starting apparatus according to claim 8 in which the means, which automatically disconnects the manually operable member from the pinion meshing device, is operated in response to the turning of the shaft by the starting motor.

10. Engine starting apparatus comprising, in combination, a motor, a helically splined shaft operated by the motor; a sleeve connected with said splines and movable along the shaft; a pinion movable along the shaft into mesh with an engine gear; driving connections between the pinion and sleeve permitting relative axial movement between the 35 pinion and sleeve; a manually operable member for moving the sleeve; and means for automatically disconnecting the manually operable member from the sleeve after the pinion 40 has been meshed and before the engine starts.

11. Engine starting apparatus according to claim 10 in which the means which automatically disconnects the manually operable member from the sleeve, is operated in response to the turning of the shaft by the motor.

12. An engine starter drive comprising, in combination, a rotatable driving member adapted to move axially into driving connection with a member of an engine to be started; a spring for urging the driving member toward the engine member; means having a manually operated actuator for causing the spring to be effective to urge the driving member 55 yieldingly against the engine member in case the driving member collides with the engine member before becoming drivingly connected therewith, and for causing the driving member to rotate while being yieldingly 60 pressed against the engine part; means

for automatically disconnecting the actuator from the driving member before the engine starts; and means for automatically disconnecting said members when the engine starts.

13. An engine starter drive comprising, in combination, a rotatable driving member adapted to move axially into driving connection with a member of an engine to be started; a spring for urging the driving member toward the engine member; means having a manually operated actuator for causing the spring to be effective to urge the driving member yieldingly against the engine member in case the driving member collides with the engine member before becoming drivingly connected therewith, and for causing the driving member to rotate while being yieldingly pressed against the engine part; a starting motor for operating the driving member; means responsive to the 70 operation of the motor for automatically disconnecting the actuator from the driving member before the engine starts; and means for automatically disconnecting said members when the engine starts.

14. An engine starter drive comprising, in combination, a rotatable drive shaft; a rotatable drive-connecting-member adapted to be moved longitudinally of the shaft into driving connection with a part of an engine 75 to be started; an intermediate drive device movable longitudinally of the shaft; means so connecting the shaft and device that relative longitudinal movement is accompanied by relative rotary movement; means connecting the drive-connecting-member and intermediate device so as to permit relative longitudinal movement between them; a spring for normally maintaining a certain normal longitudinal relation between the member and device; means having a manually operated actuator for moving the intermediate device and drive-connecting-member toward the engine part in order to connect said member and part; and means for automatically disconnecting the actuator.

15. An engine starter drive comprising, in combination, a rotatable drive shaft; a rotatable drive-connecting-member adapted to be moved axially along the shaft into driving connection with a part of an engine to be started; an intermediate drive sleeve movable axially along the shaft, and having helical spline connections with the shaft and straight longitudinal spline connections with the member; a spring for normally maintaining a certain normal longitudinal relation between the member and device; means having a manually operated actuator for moving the intermediate device and drive-connecting member toward the engine part in order to connect said member and part; and means for automatically disconnecting the actuator.

16. An engine starter drive comprising, in

combination, a rotatable drive-connecting-member movable axially into driving connection with a part of the engine to be started; manually operable means for moving the member into engagement with the part and for rotating the member in case it collides with the part before becoming drivingly connected therewith, said means comprising an actuator, a shifter mounted for concurrent longitudinal and rotary movement, and means connecting the shifter with the member so that the shifter may impart rotation to the member so that there may be relative longitudinal movement between the shifter and member; and means for automatically disconnecting the drive-connecting-member from the engine part when the engine starts.

17. An engine starter drive comprising, in combination, a rotatable drive-connecting-member movable axially into driving connection with a part of the engine to be started; manually operable means for moving the member into engagement with the part and for rotating the member in case it collides with the part before becoming drivingly connected therewith, said means comprising an actuator, a shifter mounted for concurrent longitudinal and rotary movement, and means connecting the shifter with the member so that the shifter may impart rotation to the member and so that there may be relative longitudinal movement between the shifter and member; and means for automatically disconnecting the drive-connecting-member from the engine part when the engine starts; and means for automatically disconnecting the actuator from the shifter.

18. Engine starting apparatus comprising, in combination, a motor, a shaft driven thereby, means for connecting the shaft with the gear of an engine to be started and comprising a pinion movable endwise into mesh with the engine gear and provisions whereby the pinion will be automatically demeshed when the engine starts, said connecting means including an endwise movable shaft so connected with the motor shaft that endwise movement thereof will produce rotation thereof relative to the motor shaft, means connecting the pinion with the endwise movable shaft and providing for longitudinal relative movement between them, manually operated means for moving the second shaft and pinion endwise, said means having an actuator; and means for automatically disconnecting the actuator from the manually operated means before the engine operates.

19. Engine starting apparatus comprising, in combination, a motor; a shaft driven thereby; means for connecting the shaft with the gear of an engine to be started and comprising a pinion movable endwise into mesh with the engine gear and provisions whereby the pinion will be automatically demeshed

when the engine starts, said connecting means including an intermediate endwise movable shaft so connected with the motor shaft that endwise movement of the intermediate shaft will produce rotation thereof relative to the motor shaft, and means connecting the intermediate shaft and pinion and providing for relative longitudinal movement between them; a spring adapted to urge the pinion yieldingly against the gear; manually operated means for rendering the spring operative yielding to press the pinion against the gear in case of abutment before meshing, and for moving the intermediate shaft endwise in order to rotate the pinion while it is yieldingly pressed against the gear, said manually operable means having an actuator; and means for automatically disconnecting the actuator from the manually operated means before the engine starts.

20. Engine starting apparatus comprising, in combination, a motor; a shaft operated thereby; a pinion movable endwise along said shaft into mesh with an engine gear; means for causing the pinion to be automatically demeshed from the engine gear when the engine starts; a sleeve drivingly connected with the shaft in such manner that relatively longitudinal movement between the sleeve and shaft is accompanied by relative rotary movement between them; driving connections between the sleeve and pinion providing for a limited amount of relative longitudinal movement between them, and transmitting to the pinion substantially only rotary motion until the lost motion between the sleeve and pinion is taken up; a spring for yieldingly urging the pinion against the gear while the pinion is being turned by the sleeve; manually operated means for moving the sleeve in order to mesh the pinion with the gear; and means for automatically rendering the manual means inoperative to prevent demeshing of the pinion by the starting of the engine.

21. Engine starting apparatus comprising, in combination, a motor; a shaft operated thereby; a pinion movable endwise along said shaft into mesh with an engine gear; a pinion shifter movable along the shaft and connected with the shaft in such manner that endwise movement of the shifter is accompanied by rotation thereof; lost motion connections between the shifter and pinion permitting limited longitudinal movement of the shifter relative to the pinion in case endwise movement of the pinion is arrested whereby rotary motion only will be imparted by the shifter to the pinion until the longitudinal lost motion is taken up; and manually operable means for moving the shifter.

22. Engine starting apparatus comprising, in combination, a motor; a shaft operated thereby; a pinion movable endwise along said shaft into mesh with an engine gear; a pinion shifter movable along the shaft and connected

with the shaft in such manner that endwise movement of the shifter is accompanied by rotation thereof; lost motion connections between the shifter and pinion permitting limited longitudinal movement of the shifter relative to the pinion in case endwise movement of the pinion is arrested, whereby rotary motion only will be imparted by the shifter to the pinion until the longitudinal lost motion is taken up; manually operable means for moving the shifter and including an actuator; automatic means for disconnecting the actuator from the shifter before the engine starts; and automatic means for disconnecting the pinion from the gear when the engine starts.

In testimony whereof I hereto affix my signature.
